PROCESS FOR THE DESTRUCTIVE HYDROGENATION OF HIGH BOILING-POINT HYDROCARBONS WITH THE FORMATION THEREFROM OF HYDROCARBONS HAVING A LOWER BOILING-POINT

Roland Hall Griffith, London, England, assignor to The Gas Light & Coke Company, London, England, a British company

Application January 2, 1932, Serial No. 584,412
In Great Britain January 12, 1931

13 Claims. (Cl. 196—53)

This invention relates to processes for the destructive hydrogenation of high boiling-point hydrocarbons and derivatives thereof by treatment with hydrogen, or other reducing gases such as water gas, at an elevated temperature and pressure, with the formation of hydrocarbons having a lower boiling point than the boiling point of the hydrocarbon or derivative treated. Such processes are hereinafter referred to as processes of the type described.

Instances of high boiling-point hydrocarbons the treatment of which is contemplated in this invention include coal tar, natural petroleum, asphalt, bitumen, heavy oils and oil fractions produced from these substances. The hydrocarbon derivative may be a phenolic body.

It is known to assist the reaction in destructive hydrogenation processes of the type described by the presence in the reaction sphere of a molybdenum catalyst and a promoter therefor.

It is also known to aid the reaction in such processes by employing appropriate proportions of hydrogen sulphide along with the molybdenum catalyst and promoter.

We have found, on investigating the use of a promoter with a molybdenum catalyst in processes of destructive hydrogenation of high boiling-point hydrocarbons, that if a curve of catalyst-activity be plotted, the ordinates of this curve representing the activity of the catalyst in terms of percentage yield of hydrogenation product boiling below a given temperature, for example 180° C., and the abscissa of the curve representing the atomic proportion of promoter element to molybdenum used in the process, such curve has in it an acute peak or peaks. The presence of these peaks indicates that certain closely defined proportions of promoter to catalyst give markedly better results in yield of hydrogenation product than ratios elsewhere on the curve, and the broad idea of selecting and using a peak ratio of promoter to catalyst in destructive hydrogenation processes in which a molybdenum catalyst is used aided by a promoter, is described and claimed in United States patent specification Serial No. 501,998.

We have now discovered that peaks in the catalyst-activity curve occur with varying proportions of promoter also in cases where the reaction is assisted by the joint action of a molybdenum catalyst, a promoter therefor and appropriate proportions of hydrogen sulphide, sulphur or a substance yielding hydrogen sulphide under the conditions of the reaction, and

further that the peaks occur in the same positions in the curve.

According to the present invention, therefore, a process of the type described for the destructive hydrogenation of high-boiling point hydrocarbons or derivatives thereof in the presence of a molybdenum catalyst, a promoter therefor, and hydrogen sulphide, sulphur or a substance yielding hydrogen sulphide under the conditions of the reaction, is characterized by the selection and use of a peak-ratio of promoter to catalyst; that is to say, a ratio of promoter to catalyst which is within the peak or one of the peaks of the catalyst-activity curve hereinbefore referred to.

In most cases the curve comprises two peaks, and the position of the second peak is independent of the temperature employed in the process and also of the initial hydrocarbon material submitted to the treatment. Preferably therefore, the ratio used of promoter to catalyst is the optimum ratio of the second peak of the catalyst-activity curve.

In cases where the catalyst-activity curve comprises two peaks, that portion of the curve which lies between the peaks generally represents a depression of activity; that is to say, the use of ratios between the two peaks of the curve generally results in a definite depression of activity of the catalyst below the activity the catalyst would have if it were used alone, and is, therefore, positively disadvantageous.

The free hydrogen sulphide should be present in the critical proportions, relatively to the quantity of initial material treated, which ensure the highest yield. If too much sulphur or hydrogen sulphide be present, certain undesirable reactions tend to set in. An undue excess of sulphur or hydrogen sulphide may also result in excessive sulphurization of the hydrogenation product. If too little sulphide be used its enhancing effect upon the activity of the catalyst will not be realized to the full, and may not be realized at all, especially in the event of metallic molybdenum or an oxygen compound of molybdenum being used as the catalyst. In this connection, it may be stated that the first effect of the sulphur appears to be to form a molybdenum sulphide (i. e. in the event of metallic molybdenum being used in the process), and it is the excess of hydrogen sulphide over the sulphur in combination with the molybdenum that operates to enhance the activity of the catalyst, at any rate to the remarkable degree that is characteristic of the present invention. The

actual proportion in any given case depends upon the nature and in particular the chemical constitution of the initial material treated, but is readily determinable by a simple preliminary test.

The hydrogen sulphide may either be introduced as such into the reaction sphere, or it may be formed in situ therein. In the latter case, elemental sulphur may be introduced into the reaction sphere to combine with the hydrogen therein, or conveniently carbon bisulphide may be mixed with the tar or other initial material to be treated; or again the requisite quantity of sulphur may be derived from the initial material itself. In some cases the initial material may be found to be too rich in available sulphur, in which event the said material may be blended with other initial material less rich in sulphur or sulphur-free.

20 The molybdenum catalyst may either consist of molybdenum in the elemental form, or of an appropriate molybdenum compound, for example, molybdic acid.

Similarly, the promoter may either be in the elemental form, or in the form of a suitable compound, for example, an oxygen compound or a sulphide of the element. In this connection it is to be understood that the expression "promoter element" used in this specification is intended to connote, in the case of a compound, the metal or other element with which the oxygen, sulphur, or other component of the compound is combined.

Various promoter elements have been found to give satisfactory results in the process. Preferably, however, the promoter element is one of the lighter metals, alkaline earth metals, metalloids, or solid non-metallic elements. More specifically, the following promoter elements have been found to give good results:—silicon, boron, lithium, phosphorus, calcium. Of these specific promoters, silicon, boron and phosphorus appear to be the most satisfactory.

The use as the promoter of sulphur as such is excluded from the scope of the invention, as sulphur is a substance which per se will not operate as a promoter in the process.

As previously indicated herein, it is preferable to use a ratio of promoter element to the molybdenum which is within the second peak-ratio range of the catalyst-activity curve. In the case of silicon, the second peak-ratio range is approximately 5-8:100. In the case of boron, it is approximately 7-10:100. The corresponding peak-ratio changes in the case of lithium, phosphorus and calcium are respectively:—7-7.5:100, 4-4.5:100 and 7.5-7.8:100.

The approximate values of the peak-ratios of promoter to molybdenum for the preferred promoters mentioned above are indicated on the graphs accompanying United States Patent No. 1,938,328.

In the drawings Figure 1 illustrates more or less approximately typical curves for the yield of spirit when a standard low temperature carbonization tar is subjected to destructive hydrogenation in the presence of molybdenum catalyst alone, and in the presence of molybdenum catalyst promoted by various promoters and with the addition of various amounts of sulphur in the form of carbon bisulphide. The ordinates represent the percentage of distillate boiling below 180° C. and the abscissæ represent the number of grms. of carbon bisulphide added to 100 grms. of the tar (previously topped to 200° C.).

Figure 2 shows in diagrammatic form one type of apparatus for carrying out the invention.

Referring to Figure 1, curve I represents the variation in the percentage of spirit when increasing amounts of carbon bisulphide are added to a molybdenum catalyst; curve II represents the variation in the percentage of spirit when the carbon bisulphide is added to a molybdenum catalyst-silicon promoter in which the ratio of silicon to molybdenum is within one of the peak-ratio ranges above referred to; and curve III similarly represents the variation in the yield of spirit when the molybdenum catalyst is promoted with phosphorus and the ratio of phosphorus to molybdenum is likewise within one of the peak-ratio ranges above referred to.

It will be clear from the curves that there is an optimum amount of carbon bisulphide which when added to the molybdenum catalyst alone or molybdenum catalyst mixed with a promoter gives a maximum yield of spirit from tar, and it will further be noticed that the yields of spirit using molybdenum catalyst alone with a certain amount of carbon bisulphide are always less than the yields of spirit when employing correctly promoted molybdenum with the same amount of carbon bisulphide.

It is a feature of this invention therefore that not only is the ratio of promoter to molybdenum within the peak ratio range or one of the peak ratio ranges hereinbefore referred to, but also that the process of the type described for the destructive hydrogenation of high boiling point hydrocarbons and derivatives thereof is carried out with the optimum or approximately the optimum proportion of hydrogen sulphide, sulphur or a substance yielding hydrogen sulphide under the conditions of the reaction as illustratively indicated in Figure 1 accompanying this specification.

One type of apparatus suitable for carrying the present invention into effect is shown in diagrammatic form in Figure 2 in which 1 is a reservoir for the high-boiling hydrocarbon (for example an oil or tar) to be treated, 2 is a pump delivering the oil or tar to the electrically heated catalyst vessel 5 where it reacts in the presence of a substance yielding hydrogen sulphide under the conditions of the reaction with hydrogenating gas delivered by a compressor 3 from an inlet pipe 4.

After leaving the catalyst vessel 5 the products of the reaction pass into a condenser 6 and thence into separators 7 and 9. Gas leaves the separators through pipes 8 and 11 while liquid is drawn off from the system through pipe 10.

The following examples of the invention will now be described.

Example 1

200 grams of low-temperature tar, previously topped to 200° C., and substantially free from sulphur compounds from which hydrogen sulphide would be formed under the conditions of the reaction, were heated for one hour in a 3-litre autoclave with hydrogen at an initial pressure of 110 atmospheres in the presence of 10 grams of sulphur and 10 grams of a catalyst promoter mixture consisting of molybdic acid and silica in the atomic Mo:Si ratio of 100:5.5. The hydrogenation product comprised 19 c. cs. of water and 130 c. cs. of an oil, 53% of which distilled below 180° C.

Example 2

The same tar was treated under like conditions, but with a molybdcic acid-silica catalyst promoter mixture, in which the atomic Mo:Si ratio was approximately 100:3. The product comprised 22 c. cs. of water and 140 c. cs. of an oil, 53% of which boiled below 180° C.

In Example 1, the promoter proportion was at the optimum point of the second peak of the catalyst-activity curve for silicon promoters. In Example 2, the promoter proportion was at the optimum point of the first peak of said curve.

Example 3

The same tar again was treated under conditions similar to those in Examples 1 and 2, but in this case, the atomic Mo:Si ratio was 100:4.4. This ratio is located on the catalyst-activity curve for silicon, at a point between the first and second peaks thereof and the hydrogenation product comprised 147 c. cs. of an oil, of which only 44% boiled below 180° C. This example, as will be appreciated, illustrates the harmful effect of employing a ratio of promoter to catalyst which is not in one or other of the peak ratio ranges of the catalyst-activity curve.

Example 4

The same low-temperature tar was treated under conditions similar to those obtaining in the previous examples, but with a molybdenum-boron catalyst promoter mixture, in which the atomic Mo:B ratio was 100:3.7. The product comprised 160 c. cs. of an oil, 54% of which boiled below 180° C.

It is to be understood that the expression "peak-ratio proportions" is used in the following statement of claim to denote proportions of catalyst and promoter within the peak portion of the catalyst-activity curve hereinbefore referred to with reference to United States Patent 1,938,328. Further, it is to be understood that the peak-ratio proportion is maintained in carrying out the present invention at the same proportion as that when no hydrogen sulphide is used.

I claim:—

1. A process for the destructive hydrogenation of high boiling-point hydrocarbons or derivatives thereof which consists in heating the hydrocarbon at a temperature of the order of 440° C. with hydrogen under a pressure of between 110 and 200 atmospheres in the presence of a catalyst mixture comprising molybdenum catalyst and a promoter therefor selected from the group comprising silicon, lithium, boron, phosphorus and calcium, the catalyst and promoter being in peak-ratio proportions as herein defined together with optimum proportions of a substance yielding hydrogen sulphide under the conditions of the reaction.

2. A process for the destructive hydrogenation of high boiling-point hydrocarbons or derivatives thereof which consists in heating the hydrocarbon at a temperature of the order of 440° C. with hydrogen under a pressure of the order of 200 atmospheres in the presence of a catalyst mixture comprising molybdenum catalyst and a promoter therefor selected from the group comprising silicon, lithium, boron, phosphorus and calcium, the catalyst and promoter being in peak-ratio proportions as herein defined and, as a substance yielding hydrogen sulphide under the conditions of the reaction, carbon bisulphide in optimum amount.

3. A process for the destructive hydrogenation of high boiling-point hydrocarbons or derivatives thereof which consists in heating the hydrocarbon at a temperature of the order of 440° C. with hydrogen under a pressure of the order of 200 atmospheres in the presence of a catalyst mixture comprising molybdenum catalyst and a promoter therefor selected from the group comprising silicon, lithium, boron, phosphorus and calcium, the catalyst and promoter being in peak-ratio proportions as herein defined, together with optimum proportions of a substance yielding hydrogen sulphide under the conditions of the reaction.

4. A process for the destructive hydrogenation of high boiling-point hydrocarbons or derivatives thereof which consists in heating the hydrocarbon at a temperature of the order of 440° C. with hydrogen under a pressure of the order of 200 atmospheres wherein the reaction is assisted by a molybdenum catalyst and a silicon promoter therefor, the molybdenum and silicon being in peak-ratio proportions as herein defined together with optimum proportions of a substance yielding hydrogen sulphide under the conditions of the reaction.

5. A process for the destructive hydrogenation of high boiling-point hydrocarbons or derivatives thereof which consists in heating the hydrocarbon at a temperature of the order of 440° C. with hydrogen under a pressure of the order of 200 atmospheres wherein the reaction is assisted by a molybdenum catalyst and a silicon promoter therefor, the proportion of silicon to molybdenum being between 5 and 8 per cent together with optimum amounts of a substance yielding hydrogen sulphide under the conditions of the reaction.

6. A process for the destructive hydrogenation of high boiling-point hydrocarbons or derivatives thereof which consists in heating the hydrocarbon at a temperature of the order of 440° C. with hydrogen under a pressure of the order of 200 atmospheres wherein the reaction is assisted by a molybdenum catalyst, a silicon promoter therefor, the proportion of silicon to molybdenum being between 5 and 8 per cent, and optimum proportions of carbon bisulphide, as a substance yielding hydrogen sulphide under the conditions of the reaction.

7. A process for the destructive hydrogenation of high boiling-point hydrocarbons or derivatives thereof which consists in heating the hydrocarbon at a temperature of the order of 440° C. with hydrogen under a pressure of the order of 200 atmospheres wherein the reaction is assisted by a molybdenum catalyst, a lithium promoter therefor the molybdenum and lithium being in peak-ratio proportions as herein defined, and optimum amounts of a substance yielding hydrogen sulphide under the conditions of the reaction.

8. A process for the destructive hydrogenation of high boiling-point hydrocarbons or derivatives thereof which consists in heating the hydrocarbon at a temperature of the order of 440° C. with hydrogen under a pressure of the order of 200 atmospheres wherein the reaction is assisted by a molybdenum catalyst, a lithium promoter therefor, the proportion of lithium to molybdenum being between 7 and 7.5% and optimum amounts of a substance yielding hydrogen sulphide under the conditions of the reaction.

9. A process for the destructive hydrogenation of high boiling-point hydrocarbons or deriv-

atives thereof which consists in heating the hydrocarbon at a temperature of the order of 440° C. with hydrogen under a pressure of the order of 200 atmospheres wherein the reaction is assisted by a molybdenum catalyst, a lithium promoter therefor, the ratio of lithium to molybdenum being between 7 and 7.5%, and optimum proportions of carbon bisulphide, as a substance yielding hydrogen sulphide under the conditions of the reaction.

10. A process for the destructive hydrogenation of high boiling-point hydrocarbons or derivatives thereof which consists in heating the hydrocarbon at a temperature of the order of 440° C. with hydrogen under a pressure of the order of 200 atmospheres wherein the reaction is assisted by a molybdenum catalyst, a boron promoter therefor, the proportion of boron to molybdenum being between 7 and 10%, and optimum proportions of carbon bisulphide as a substance yielding hydrogen sulphide under the conditions of the reaction.

15. A process for the destructive hydrogenation of high boiling-point hydrocarbons or derivatives thereof which consists in heating the hydrocarbon at a temperature of the order of 440° C. with hydrogen under a pressure of the order of 200 atmospheres wherein the reaction is assisted by a molybdenum catalyst, a boron promoter therefor the molybdenum and boron being in peak-ratio proportions, and optimum proportions of a substance yielding hydrogen sulphide under the conditions of the reaction.

20. A process for the destructive hydrogenation of high boiling-point hydrocarbons or derivatives thereof which consists in heating the hydrocarbon at a temperature of the order of 440° C. with hydrogen under a pressure of the order of 200 atmospheres wherein the reaction is assisted by a molybdenum catalyst, a boron promoter therefor, the proportion of boron to molybdenum being between 7 and 10%, and optimum proportions of a substance yielding hydro-

gen sulphide under the conditions of the reaction.

12. A process for the destructive hydrogenation of high boiling-point hydrocarbons or derivatives thereof which consists in heating the hydrocarbon at a temperature of the order of 440° C. with hydrogen under a pressure of the order of 200 atmospheres wherein the reaction is assisted by a molybdenum catalyst, a boron promoter therefor, the proportion of boron to molybdenum being between 7 and 10%, and optimum proportions of carbon bisulphide as a substance yielding hydrogen sulphide under the conditions of the reaction.

13. A process for the destructive hydrogenation of high boiling-point hydrocarbons or derivatives thereof which consists in heating the hydrocarbon at a temperature of the order of 440° C. with hydrogen under a pressure of the order of 200 atmospheres in the presence of a catalyst mixture comprising a molybdenum catalyst, and a promoter therefor selected from the group comprising silicon, lithium, boron, phosphorus and calcium, the catalyst and promoter being in peak-ratio proportions as herein defined, and a substance yielding hydrogen sulphide in amounts that will yield under the conditions of the reaction, from 3 to 6% of hydrogen sulphide based on the amount of hydrocarbon being treated.

ROLAND HALL GRIFFITH.
